UNITED STATES PATENT OFFICE.

WILLIAM HUCKS AND WILLIAM HUCKS, JR., OF CAMDEN-TOWN, LONDON,
ENGLAND.

APPARATUS FOR USE IN DISPENSING LIQUIDS.

SPECIFICATION forming part of Letters Patent No. 694,646, dated March 4, 1902.

Application filed May 28, 1901. Serial No. 62,280. (No model.)

To all whom it may concern:

Be it known that we, WILLIAM HUCKS and WILLIAM HUCKS, Jr., engineers, subjects of the King of Great Britain, residing at 22 Oval road, Camden-Town, in the county of London, England, have invented new and useful Improvements in Apparatus for Dispensing Aerated Liquids, of which the following is a specification.

- 10 Our invention relates to apparatus for dispensing aerated liquids wherein the aerated liquid is drawn off from the container thereof through a valve into a closed intermediate vessel, from which it is afterward poured for 15 consumption; and the object of our invention is to provide simple and efficient apparatus for the purpose which is cheap in first cost, very readily operated, and not liable to readily get out of order.
- 20 According to our invention the intermediate vessel is employed so that it forms the handle or is operated with the handle by which the closure of the intermediate vessel is first effected, and then the valve is opened 25 by the combined movement of the said handle, the said handle afterward allowing the valve to close and then separating the closing device and the intermediate vessel, which vessel can then be brought into a position to dis- 30 charge its contents into a glass or other receptacle for consumption.

We will describe with reference to the accompanying drawings arrangements or constructions of apparatus according to our invention.

35 Figure 1 is a front elevation, and Fig. 2 is a longitudinal section, of an apparatus constructed in accordance with this invention. Fig. 3 is a detail showing one of the cam- 40 grooves for operating the valve. Fig. 4 is a front elevation, and Fig. 5 a longitudinal section, of a similar apparatus, showing a modification of the valve-operating mechanism; and Fig. 6 is a detail in section of the valve- 45 operating arrangement.

Referring first to Figs. 1, 2, and 3, A is the end of a pipe or attachment to the pipe leading from the container of the aerated liquid,

which pipe or attachment projects from a partition, wall, or standard B and toward its 50 end has a seating a for a valve b, which opens inwardly. The said valve is carried in a piece c, having a squared (or equivalently-formed) projecting end d and laterally-projecting pins or trunnions e engaging with cam-grooves f 55 in a part A', projecting from the end of the pipe or attachment A beyond the valve-seat- ing a. Mounted upon the said pipe or at- tachment A is a sleeve C, extending beyond the end of the said pipe or attachment and 60 having an end piece D screwed into it, which end piece has a squared or equivalently- shaped recess g fitting upon the projection d of the piece c, which carries the valve b. The said sleeve C also carries a nozzle E, which 65 when the valve b is opened is in communica- tion with the pipe or attachment A, leading from the aerated-liquid container. On the sleeve C, near the said nozzle, is a lug h, to which is independently pivoted at h' a holder 70 F for a bottle G or other receptacle, which con- stitutes the intermediate vessel or receptacle for receiving the drawn-off aerated liquid prior to its being poured therefrom for consumption. The mouth of the said bottle or receptacle is in 75 such a position as to receive the nozzle E, whose exterior is provided with a plug i of a material suitable to make a tight closure of the mouth of the said bottle or receptacle. When aerated liquid is to be drawn off, the 80 bottle or receptacle G is moved like a handle; but before any rotary movement is imparted to the sleeve C the holder F moves on its joint at h' sufficiently to allow the mouth of the bottle or receptacle G to be tightly closed by 85 the plug i, surrounding the nozzle E, and then by continued movement of the bottle or receptacle G and holder F the sleeve C is partly rotated, so that the recess g in the end piece D, carried by the sleeve C, partly ro- 90 tates the carrier c of the valve b, so that the pins or trunnions e are acted upon by the cam-grooves f in the part A', projecting from the end of the pipe or attachment A, and the valve b is thereby opened and aerated liquid 95 passes into the bottle or receptacle G. When

- the said bottle or receptacle G is released, a torsional spring H returns the sleeve C to its normal position, and the valve b is closed by the cam-grooves f acting on the pins or trunnions e, and then the bottle or receptacle G, with its holder F, can be turned upon the hinge-joint h', causing the mouth of the bottle or receptacle G to come away from the nozzle E and permitting the bottle or receptacle G to be turned so that its contents can be poured into a glass for consumption. The spring H is preferably inclosed by a casing I. To make a fluid-tight joint between the sleeve C and the pipe or attachment A, a conical projection k is formed on the end of the said pipe or attachment A to fit in close contact with a corresponding conical recess l, formed in the sleeve C.
- In Figs. 4, 5, and 6 the parts corresponding to those described with reference to Figs. 1, 2, and 3 are marked with the same letters of reference. In this modification the valve a is normally maintained closed against its seat b by a spring a', one end of which bears on a shoulder in a recess a'', formed in the end of the pipe or attachment A, the said valve and spring being inclosed in a cap or casing b', (screwed onto the end of the said pipe or attachment A,) having a passage in the end surrounded by the seat b for the valve a. This valve a is forced from its seat by cam-shaped projections f'' on the inner face of the end piece D of the sleeve C, which projections when the said sleeve is partly rotated on the pipe or attachment A for the purpose of drawing off the aerated liquid press on a bar i, connected to the valve a by a screwed stem i', so as to force the valve a from its seat against the counteracting pressure of the spring a' and of the pressure of the liquid within the container. To prevent the valve from turning when operated by the cam projections, cheek-pieces c' are provided on the end of the casing b', between which cheeks the bar i is guided in its movements. When the sleeve C is in its normal position, the valve a is allowed to close by reason of the cam-shaped projections f'' being cut away from that portion of the inner face of the end piece D which is opposite the bar i. To insure a liquid-tight joint between the sleeve C and the pipe or attachment A, an inclined shoulder k is formed on the said pipe or attachment, which shoulder is held in contact with a corresponding inclined surface l in the sleeve C by a spring m, interposed between a nut or projection n on the pipe or attachment A and the back of the rose or plate p, by which the apparatus is fixed to a wall, partition, or standard B. Projecting from the front of the rose or plate p is a socket q, in which the sleeve C turns, the said socket having a slot r therein, through which slot a stud or pin s is screwed into the sleeve C, the length
- 65 of the said slot limiting the extent of ro-

tation of the sleeve by the pin s coming against the ends of the said slot. In the shoulder k on the pipe or attachment A is a notch k', and in the inclined surface l in the sleeve, which is in contact with the said shoulder, is a similar notch l'. These notches coincide with each other when the sleeve is in its normal position (shown in Fig. 5) to allow of "sniffling" (relief of superfluous gas) from the bottle or receptacle G. In Fig. 4 the apparatus is shown in full lines in its normal position, with the nozzle E inserted in the mouth of the bottle or receptacle G. To charge the bottle or receptacle with the aerated liquid, the sleeve C is turned (using the bottle or receptacle G as a handle) into the lower position, (shown by dotted lines, Fig. 4,) this movement causing the valve a to be forced by the cam projections f'' from its seat b and admit the liquid to the bottle or receptacle G through the nozzle E. Afterward by removing pressure from the bottle or receptacle G the sleeve C will be returned by the spring H to the position shown by full lines, in which the notches k' l' will coincide and admit of the sniffling (escape of superfluous gas) of gas from the interior of the bottle or receptacle G, and thereby prevent sudden puffs of gas from the bottle or receptacle when its mouth is removed from the nozzle E. To discharge the contents of the bottle or receptacle into a glass or other vessel, it and its holder are turned on the joint h' into the higher position. (Shown in dot-and-dash lines in Fig. 4.)

If desired, in both the foregoing and following arrangements in order to take the strain off the bottle or receptacle G, if it be made of glass, the holder F may be provided with a metal part, as at f, to receive the thrust of the hand of the user.

We claim as our invention--

1. Apparatus for dispensing aerated liquors, comprising a container having an outlet, a valve therein, and a closing device on said outlet, in combination with a vessel, a holder for the vessel, and a pivot for the holder independent of the valve, said holder adapted when rotated to first close the vessel's mouth against the closing device and upon further rotation to open the valve, substantially as described.

2. Apparatus for dispensing aerated liquors, comprising a container having an outlet, a valve therein and a closing device on said outlet, in combination with a rotatable sleeve, a holder pivoted on the sleeve and adapted to carry a vessel, whereby when the holder is turned on its pivot, the mouth of the vessel is first closed by the closing device and then the valve is opened, as described.

3. Apparatus for dispensing aerated beverages, comprising a container, an outlet-pipe therefrom and rigid therewith, a valve-stem parallel with the outlet-pipe, a valve on the stem, a closing device and a holder pivoted

to the outlet-pipe independently of the valve, substantially as described.

4. Apparatus for dispensing aerated beverages, comprising a container, an outlet-pipe therefrom, a valve and a valve-stem parallel with the outlet-pipe, a closing device, a rotatable sleeve on the outlet-pipe and a holder pivoted to the rotatable sleeve, substantially as described.

In testimony whereof we affix our signatures in presence of two witnesses.

WILLIAM HUCKS.
